BLIND DITCHER

Filed May 5, 1928

UNITED STATES PATENT OFFICE

HARLOW ISAAC UMBARGER, OF BUFORD, ALBERTA, CANADA

BLIND DITCHER

Application filed May 5, 1928. Serial No. 275,465.

This invention relates to improvements in blind ditchers and the objects of the invention are to provide a device of this character of few parts capable of minute adjustment 5 through which land may be drained efficiently and at comparatively low cost.

A further object of the invention is to provide in combination with the means for adjustment, means for the ready removal of the 10 drill or drag swells and the provision of means for supplying liquid to the drill or swells in order to obviate friction between the ground and the device and at the same time firmly set the ditch produced.

With these and other objects in view the device comprises essentially a beam adapted to carry a drill or swell by means of vertically adjustable standards and provided with a water tank formed with a delivery to the 20 drill or swells beneath the ground.

Referring to the drawings,

Figure 1 is a side elevation of my improved ditcher showing the drill in normal working position beneath the ground level,

Figure 2 is a plan view of the same, and Figure 3 is a sectional detail on the line 3—3 of Figure 1.

Referring to the drawings, 10 designates the beam of the ditcher formed with the usual 30 clevis 11 at the front end adapted for the draft attachment. This beam is carried by the land wheels 12 and the gauge wheel 13, the former being carried on a crank axle 14 mounted on the beam as at 15, whereby the front of the beam may be elevated or lowered 35 through the usual lever 16 in rigid connection with the crank shaft and adapted to engage and disengage with the rack 17 through the usual latch and trigger 18 and 19, respectively. The gauge wheel may be vertically adjusted by means of set-screws 20.

Coming now to a very salient and essential feature of my invention, the drill or swell 20^a of this device is adjustably mounted on the beam in any desirable position, but preferably centrally disposed, as illustrated, by means of the adjustable colter member 21 formed with a knife edge and the adjustable standard 22, each formed with orifices 23 40 adapted to be engaged by bolts, set-screws

or the like 24 positioned on the beam to traverse the slots 25 in the beam through which the colter member and standard member are adapted to pass.

In order to brace said members I provide 55 a bracing member 26 provided with orifices for adjustable engagement with these members by means of the usual bolts or the like, as illustrated, and pivotally secured to the beam by means of the clevis or other suitable means 27. The colter member 21 is provided with a colter 28 integral therewith and formed at the rear thereof with a slot adapted for the engagement of the front end of the 60 drill or swell which may be detachably engaged therewith.

Additional drag swells 34 of different sizes may be fitted to the swell 20^a. These drag swells are chiefly used where a small lake or 65 spring is to be drained. The drag swells 34 being formed hollow and having openings 35 therein, water will follow through, thereby moistening the ground, and reducing friction on the drag swells and also setting the 70 walls of the drain or ditch.

The drill or drag swell 20^a may be made in any size according to the desired size of ditch required. This drill or swell is formed in two pieces. The outer casing 20^b is integral with the standard 22, while the inner portion 20^c is 75 detachably secured to the outer casing by the pin 29.

It will be understood from the foregoing that minute adjustment of the drill may be obtained through the colter member and the rear standard member with relation to the beam while through the adjustment of the lever 16 and the gauge wheel 13 further adjustment to suit practically any conditions may be obtained.

In order to obviate friction between the ground and the drill or swell 20^a and in order to firmly set the walls of the ditch, I provide means for supplying liquid to the drill in the form of a water tank or the like 30 mounted in any desirable manner on the beam, provided with a delivery line 31 adapted to extend to the narrowed portion of the drill in any desirable manner, which may take the 85 form, as illustrated, secured to the rear of the 90 103

colter member 21 by suitable brackets 32. A valve member 33 is provided in the line in order to control the flow of liquid.

In operation it will be seen that the drill is placed in the ground to the desired depth, adjustment being effected by the adjustable colter member 21 and standard member 22, further adjustments being effected as desired by means of the lever 16 and gauge wheel 13. The drill is then drawn through the ground in the usual way controlled by the operator and the valve 33 of the pipe line is opened to the desired extent to allow liquid to flow over the drill thereby avoiding friction with the ground, at the same time firmly setting the walls of the ditch.

The colter member 21, it will be understood, is formed with a knife edge which during the operation may facilitate the forming of the ditch at the same time forming a further cut in the ground which will facilitate the draining of water from the surface to the ditch.

From the foregoing, it will be seen that ditches to any practical depth may be obtained and that the improved ditcher, as described, will facilitate the movement of the device through the ground with a minimum of friction and at the same time will make a compact pressed surface to the ditch and ensure the same remaining in the form of a ditch or drain pipe for an unlimited period.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:—

1. An improved ditcher comprising in combination, a beam carried by adjustable land wheels, an orificed colter member and an orificed standard member in parallel relation to one another adjustably connecting with the beam through slots formed therein, bolt members traversing the beam slots adapted to engage the orifices in the colter member and standard member, a colter integral with the lower end of the colter member, a drill carried by the standard member in detachable engagement with the colter, a pivotal bracing member anchored to the beam, common to and connecting with the upper end of the colter member and standard member, a water tank carried on the beam, a delivery line in connection with the tank connected with the rear surface of the colter member, and directed to discharge a jet of water over the forward portion of the drill, and drag swells in pivotal attachment with the drill.

2. An improved ditcher comprising in combination, a beam carried by adjustable land wheels, a rack on the beam, an operat-

ing lever connected with the forward wheels and associated with the rack for vertically adjusting the forward end of the beam, an orificed colter member and standard member in parallel relation adjustably connected with the beam through slots formed therein, bolt members traversing the beam slots adapted to engage the orifices in the colter member and the standard member, a colter integral with the lower end of the colter member, a drill carried by the standard member in detachable engagement with the colter, a pivotal bracing member anchored to the beam and connected with the upper end of the colter member and standard member, and a plurality of drag swell in pivotal attachment with the drill, said drag swells having orifices therein for the passage of a fluid.

3. The device as claimed in claim 2 in which the drag swells are secured to a detachable connecting member mounted within the drill.

In witness whereof I have hereunto set my hand.

HARLOW ISAAC UMBARGER.
